His Attorney.

UNITED STATES PATENT OFFICE

LOUIS W. THOMPSON, OF SCHENECTADY, NEW YORK, ASSIGNOR TO GENERAL ELECTRIC COMPANY, A CORPORATION OF NEW YORK

ELECTRICAL REGULATOR

Application filed August 28, 1930. Serial No. 478,463.

My invention relates to electrical regulators, and particularly to improvements in rheostatic type regulators which are provided with auxiliary quick response regulating means.

It is an object of my invention to provide a new and improved electrical regulator which is characterized by ruggedness and quick action.

10 It is another object of my invention to provide a rheostatic regulator, which has auxiliary quick response means, with a novel and uniformly acting anti-hunting means.

My invention will be better understood 15 from the following description taken in connection with the accompanying drawing, and its scope will be pointed out in the appended claims.

Referring now to the single figure of the 20 accompanying drawing, which is a diagrammatic illustration of a preferred embodiment of my invention as applied to the regulation of the voltage of a three-phase alternating current power circuit 1, which is energized 25 by a three-phase alternating current generator 2. Generator 2 comprises an armature 3 to which circuit 1 is connected, and a field winding 4 which is energized from the armature 5 of a shunt wound exciter 6, whose 30 shunt field winding 7 has in circuit therewith a fixed regulating resistance 8 and a variable rheostatic resistance 9. As shown by way of example, resistance 9 is varied by a rheostat arm 10, which slides thereover and which is 35 in contact with a conducting bar 11. The arm 10 is supported by a nut 12, which is in threaded engagement with the threaded extension 13 of the shaft of the armature 14 of a small reversible electric motor. Reversal of 40 this motor is secured by selectively energizing its oppositely wound field windings 15 and 15' by means of a pair of contactors 16 and 17. These contactors, when energized, 45 complete a circuit from a power supply circuit 20 through one or the other of the field windings, and the armature in series. Contactors 16 and 17 have their energizing circuits completed through a pair of limit switches 21 and 22 respectively, these limit 50 switches being actuated by a projection 23 on

the nut 12 whereby their circuits are opened whenever nut 12 reaches either extreme limit of its travel.

As the small operating motor possesses considerable inertia, and as there is always more or less friction in motor-operated rheostats of the type just described, such devices are relatively slow acting, and consequently it has been found desirable to provide additional means for producing quick changes in the value of the regulating resistance in the exciter field circuit. For this purpose contactors 18 and 19 are provided and arranged to control circuits for short-circuiting resistances 9 and 8 respectively. Contactor 19 being arranged normally to short-circuit resistance 8, while contactor 18 normally maintains the short-circuit around resistance 9 open.

For controlling contactors 16, 17, 18, and 19 I provide a circuit controller comprising contacts 24, 25, 36, and 37 which are mounted on a movable element 30 by means of supporting members 28, 29, 39, and 40. Members 28 and 29 are resilient and the contacts are so arranged that upon movement of member 30 in either direction contacts 24 or 25 engage a rotatable cooperating cam contact 26 before either contact 36 or 37 engages a rotatable cooperating contact 38. These contacts are also all insulated from each other by the insulating material shown on element 30. Member 30 is mounted on an arm 31, which connects to a device which responds to changes in the voltage in circuit 1. Any suitable device operating in this manner may be used, the device illustrated being a three-phase torque motor 32, whose windings are connected to the three conductors of circuit 1 through three current limiting resistors 33 and three adjustable resistors 34. A single operating lever 35 is shown for adjusting the resistors 34 simultaneously.

The torque motor is so connected, and the resistances are so adjusted that at normal voltage none of the contacts supported by element 30 are in engagement with their cooperating rotating contacts, while if the voltage of circuit 1 rises above normal an unbalanced counterclockwise torque is produced,

thereby moving member 30 downwardly, and causing contacts 25 and 37 to move toward their respective cooperating contacts, while if the voltage of circuit 1 falls below normal 5 an unbalanced clockwise torque is produced thereby causing contacts 24 and 36 to move upwardly toward their cooperating contacts 26 and 38 respectively.

A shaft 41, on which are fastened the 10 rotatable contacts 26 and 38, is arranged to be rotated at a uniform speed by any suitable means, the means shown being a small, single-phase, self-starting synchronous motor 42, of the type commonly used in electric clocks. 15 This motor may be energized from any suitable source, and as shown it is energized from one of the phases in circuit 1 through a suitable step-down transformer 43.

To dampen the motion of arm 31, a suitable 20 retarding means such as the device 44 is employed. This device is the equivalent of an ordinary dashpot and consists of a vane moving in a heavy viscous liquid, such as heavy oil.

25 Although I have shown my invention as applied to the regulation of the voltage of a three-phase alternating current circuit, it will be obvious to those skilled in the art that my invention is not so limited, and that any suitable means for moving arm 31 up and down with variations from normal of any one of a number of operating conditions to be regulated might be employed without departing from my invention in its broader aspects. It 30 will also be obvious to those skilled in the art that it is not necessary to use an exciter, and that the regulating resistances might be connected in the field circuit of the regulated dynamo-electric machine if desired, although 35 it is usually desirable to employ the exciter as in such case the current which the regulator must handle will be much smaller than if no exciter is used.

The energizing circuits for contactors 16 45 and 17 are from one side of supply circuit 20 through limit switches 21 and 22 respectively, through the contactors to movable contacts 25 and 24 respectively, thence through a rotatable cam contact 26, shaft 41, rotatable 50 conducting member 27 to the other side of circuit 20. The energizing circuits for contactors 18 and 19 are from one side of the circuit 20 to the contactors, through contacts 36 and 37 respectively to rotatable conducting member 38, thence through shaft 41 to rotatable conducting member 27, and thence to the other side of circuit 20.

The operation of the illustrated embodiment of my invention is as follows. With the 60 voltage of circuit 1 normal, movable element 30 will be in the mid-position, and contactors 16, 17, 18, and 19 will be deenergized. Resistance 8 will be short-circuited and resistance 9 will be of the proper value to give the excitation necessary to produce normal voltage un-

der the circuit conditions existing at this time. If now circuit conditions change in a manner to cause the voltage of circuit 1 to rise torque motor 32 will cause movable element 30 to move downwardly, thereby causing an intermittent engagement between contact 25 and rotatable contact 26, due to the irregular surface of the latter. This intermittent engagement of these two contacts will 70 energize contactor 16, thereby to complete a circuit to the small operating motor of the rheostat, which will rotate in such a direction as to cause nut 12 to move to the left, thereby to increase the resistance of the rheostat, and decrease the excitation of the field circuit of the exciter 6, and hence the excitation of the alternator 2. Due to the intermittent engagement of these contacts, the operation of the 75 motor will be intermittent, thereby providing an effective anti-hunting means to prevent an over-running of the motor, and hence an over-running of the rheostat. Also, due to the fact that contact 26 is rotating, there will be a wiping action between the surfaces 80 of contact 26 and contact 25, this action serving to keep the contacts clean whereby a minimum resistance is always offered to the flow of current between these contacts. Although I have shown contact 26 as a rotatable cam, it will be obvious to those skilled in the art 85 that my invention is not limited to this precise arrangement, and that any equivalent means for producing a contact whose contact-making surface moves periodically in the path of motion of contact 25 and which moves uniformly in a transverse direction to the motion from contact 25 could be employed without departing from my invention in its 90 broader aspects. If the change in voltage on circuit 1 has been small, a few engagements of 95 contacts 25 and 26 will suffice to change the excitation of machine 2 enough to restore the voltage to normal. It will be clear, however, that the greater the change in voltage on circuit 1, the greater the torque produced by motor 32, and hence the greater the pressure with which contact 25 is pressed against contact 26. Due to the resiliency of the mounting member 28, this will mean that contact 25 100 remains longer in engagement with contact 26, thereby increasing the average time the circuit of the operating motor is closed, and hence increasing the speed with which this motor changes the resistance in the exciter field circuit. The vibratory motion of contact 25 which is produced by its engagement with the cam 26, is transmitted by the resilient connection 28 to the movable means 30, and thence through means 40 to contact 37, thereby causing vibratory motion of this contact. If now the rise in voltage on circuit 1 105 is great enough, member 28 will be flexed enough to allow contact 37 to come into engagement with member 38, thereby completing the circuit for the operating coil of contact 110 115 120 125 130

tactor 19, with the result that the short circuit around resistance 8 is opened, thereby suddenly inserting a comparatively large resistance in the field circuit of the exciter 7. 5 This has the effect of quickly reducing the excitation of the exciter, and hence the excitation of machine 2. However, due to the fact that contact 37 has a vibratory motion, the operation of contactor 19 will be intermittent, thus providing an effective anti-hunting 10 means for the quick acting portion of the regulator. If, however, the rise in voltage on circuit 1 is very great, the force with which torque motor 32 presses contact 25 against cam contact 26 will be so great that all the 15 vibratory motion of contact 25 will be absorbed in its resilient supporting means, with the result that contact 37 will not leave its contact member 38, and hence contactor 19 20 will be continuously energized. When the voltage of circuit 1 returns to normal, element 30 will return to its mid-position, thereby again short-circuiting resistance 8, and stopping the operating motor of the rheostat. If 25 the rheostat has not moved far enough to insert sufficient resistance to compensate for the circuit changes causing the increase in voltage, the above described operation will again take place until the new value of the resistance 30 of the rheostat is sufficient to cause normal voltage. It will thus be seen that the speed of operation of my regulator is dependent upon the degree of change of the conditions to be regulated.

35 If now the voltage of circuit 1 is decreased, the torque of motor 32 will be such as to cause contact 24 to engage contact 26, with the result that the operating motor of the rheostat is turned in the opposite direction, 40 through the energization of contactor 17, thereby to decrease the resistance in the exciter field circuit. If the fall in voltage is great enough, contact 36 will engage contact 38, thereby energizing contactor 18 with the 45 result that all of resistance 9 is short-circuited, thus suddenly removing a comparatively large resistance from the exciter field circuit, with the result that a quick increase in the excitation of the exciter, and hence of 50 machine 2 is produced.

While I have shown and described a particular embodiment of my invention, it will be obvious to those skilled in the art that changes and modifications may be made without departing from my invention, and I, therefore, aim in the appended claims to cover all such changes and modifications as fall within the true spirit and scope of my invention.

60 What I claim as new and desire to secure by Letters Patent of the United States is:

1. A regulating system comprising, in combination, a dynamo-electric machine, a circuit for controlling the field excitation of said machine, a slow-acting rheostat in said circuit, a normally open short circuit for said rheostat, a normally short circuited resistance in said circuit, and means responsive to increases and decreases of an electrical condition to be regulated for causing said rheostat to respectively increase or decrease its resistance, said means being responsive to further increases and decreases of said condition for respectively opening the short circuit across said additional resistance or completing the short circuit about said rheostat. 70
2. A regulating system comprising, in combination, a dynamo-electric machine, a circuit for controlling the field excitation of said machine, slow acting means for gradually changing the resistance of said circuit, quick acting means for producing sudden large changes in the resistance of said circuit, means responsive to departures from normal of an electrical condition to be regulated for actuating said slow acting means, said condition responsive means being responsive to further departures from normal of said condition for actuating said quick acting means, and anti-hunting means for causing the action of said condition responsive means to be intermittent at a uniform rate which is independent of the electrical condition of said dynamo-electric machine. 80 85 90 95
3. A regulating system having, in combination, a dynamo-electric machine, a circuit for controlling the field excitation of said machine, a slow acting rheostat in said circuit, a normally open short circuit for said rheostat, a normally short circuited resistance in said excitation control circuit, means responsive to increases in the value of an electrical condition to be regulated for causing said rheostat to increase its resistance, said means being responsive to further increases in said condition for opening the short circuit across said additional resistance, said means also being responsive to decreases in the value of said condition for causing said rheostat to decrease its resistance, said means in addition responding to further decreases in the value of said condition for short circuiting said rheostat, and anti-hunting means associated with said condition responsive means for causing its action to be intermittent. 100 105 110 115
4. In combination, a circuit whose resistance controls the field excitation of a dynamo-electric machine, one of whose electrical conditions is to be regulated, a slow acting rheostat in said circuit, an additional resistance in said circuit, means normally short circuiting said resistance, means responsive to variations in said electrical condition for causing said rheostat to vary its resistance in a manner to cause the excitation of said machine to vary so as to restore said condition to normal, said means being responsive to further changes in the value of said condition. 120 125 130

- dition for causing said rheostat to be short circuited or for causing the short circuit about said additional resistance to be removed depending upon whether said condition is below or above normal respectively, and anti-hunting means for causing the action of said condition responsive means to be intermittent at a uniform rate which is independent of the amount of resistance in said excitation control circuit.
5. A regulating system comprising, a control circuit whose resistance controls the value of a condition to be regulated, electro-responsive means for slowly varying the resistance of said circuit, electroresponsive means for suddenly making large variations in the resistance of said circuit, means movable in accordance with departures of said regulated condition from a normal value, a pair of contacts mounted on said movable means, one of said contacts being resiliently mounted, a contact whose contact-making surface has a uniform periodic motion in the path of motion of said resiliently mounted contact for connection therewith, a contact whose contact-making surface is stationary with respect to the path of movement of the other movable contact for cooperation therewith, said movable contacts being so arranged that upon movement of said condition responsive means said resiliently mounted contact first engages its cooperating contact, whereby a vibrating motion is imparted to the other movable contact through the resilient mounting means, a circuit including said first-mentioned electroresponsive means and said first-mentioned pair of cooperating contacts, and a separate circuit including said second-mentioned electroresponsive means and said second-mentioned cooperating contacts.
6. An electrical regulator for cumulatively controlling two circuits which respectively control means for producing relatively slow and quick regulating changes comprising means movable in accordance with changes in the magnitude of a condition to be regulated, a pair of contacts mounted thereon, one of said contacts being resiliently mounted, a contact cooperating with said resiliently mounted contact, the circuit controlling surface of said cooperating contact having a wiping motion transverse to the path of motion of said resiliently mounted contact and a uniform periodic vibratory motion in the path of movement of said resiliently mounted contact, a contact cooperating with the other movable contact, said contact having a wiping motion transverse to the path of motion of the movable contact with which it cooperates, said contact being so arranged that upon movement of said movable means in response to changes in the regulated condition said resilient contact first engages its cooperating contact, whereby a vibratory motion is trans-

mited to the other movable contact through the resilient mounting means, and upon a further change in the regulated condition the said other movable contact intermittently engages its cooperating contact. 70

7. A voltage regulating system comprising, a power circuit, a dynamo-electric machine for energizing said circuit, a field winding circuit for said machine, an exciter for said field circuit, a field circuit for said exciter, a rheostat in the exciter field circuit, a normally open short circuit around said rheostat, a normally short circuited additional resistance in said exciter field circuit, a contact in the form of a wheel with an uneven periphery, a second contact in the form of a wheel with a smooth periphery, means for rotating said contacts on their respective axes at a uniform speed, means movable in accordance with departures of the voltage of said power circuit from a predetermined normal value, a pair of resiliently mounted contacts on said movable means for respectively engaging the uneven periphery of said first-mentioned rotating contact depending upon whether the voltage is above or below normal, a second pair of contacts on said movable means for respectively engaging the smooth periphery of said second-mentioned rotating contact upon further changes in the voltage above or below normal, circuits controlled by said resiliently mounted contacts when they engage their rotating cooperating contact for causing said rheostat to vary its resistance, and circuits controlled by said other movable contacts when they engage their rotating cooperating contact for respectively short circuiting said rheostat and opening the short circuit around said additional resistance. 90

8. A regulating arrangement for maintaining substantially constant a condition to be regulated comprising, operating means including, relatively sensitive means for relatively slowly regulating said condition, relatively insensitive means for relatively quickly regulating said condition, and mechanical anti-hunting means associated with both said relatively sensitive and said relatively insensitive means for causing their actions to be intermittent. 105

9. The combination with a machine, of means for regulating an operating condition of said machine, said means acting in response to relatively small variations in said condition to cause restoration of said condition in relatively small increments whose time durations vary in proportion to the amount of change of said condition, said means acting in response to relatively large variations in said condition to cause restoration of said condition in relatively large increments whose time durations vary in proportion to the amount of change of said condition. 110

10. The combination with a machine, of regulating means for an operating condition 125

of said machine, said means acting on relatively small changes in said condition to cause relatively slow intermittent restoration of said condition in relatively small steps, said means acting to cause said restoration to be more nearly continuous as larger changes in said condition occur, said means acting to cause relatively rapid intermittent restoration of said condition in relatively large steps when the variations in said condition exceed a predetermined amount, and said means acting to make said relatively rapid restoration continuous when the variation in said condition substantially exceeds said predetermined amount.

11. In an electrical regulator, a device for converting variations in a condition to be regulated into mechanical motion, a cam contact, a pair of resiliently mounted contacts operated by said device and arranged to respectively engage said cam contact upon relatively slight decreases or increases from a normal value of the regulated condition, a substantially circular contact wheel, a second pair of contacts operated by said device and arranged to respectively engage said circular contact wheel upon relatively large increases or decreases from a normal value of the regulated condition, and means for rotating said cam contact and said wheel contact.

30 In witness whereof I have hereunto set my hand this 27th day of August, 1930.

LOUIS W. THOMPSON.
